UNITED STATES PATENT OFFICE.

WILLIAM HENRY MORGAN, OF ALLIANCE, OHIO.

FORGING, FLANGING, AND OTHER PRESS.

1,295,189.

Specification of Letters Patent.

Patented Feb. 25, 1919.

Application filed February 25, 1918. Serial No. 219,088.

To all whom it may concern:

Be it known that I, WILLIAM HENRY MORGAN, a citizen of the United States, and a resident of Alliance, in the county of Stark 5 and State of Ohio, have invented certain new and useful Improvements in Forging, Flanging, and other Presses; and I do hereby declare the following to be a full, clear and exact description of the invention, such 10 as will enable others skilled in the art to which it appertains to make and use the same.

My invention relates to improvements in forging, flanging and other presses.

15 Heretofore presses designed for heavy work, have been operated by hydraulic mechanism which is complicated in construction, and requires constant attention, frequent repairs and adjustment of parts 20 in order to keep them in proper working condition.

The object of this invention is to simplify and consequently cheapen the cost of construction and upkeep, by dispensing with 25 the hydraulic devices, and actuating the movable platen both in its initial and final or power strokes, by mechanical devices actuated by a motor or motors, preferably electric motors.

30 With these objects in view my invention consists in the parts and combinations of parts as will be more fully explained and pointed out in the claims.

In the accompanying drawings, Figure 1 35 is a view partly in side elevation and partly in section of my improved press and Fig. 2 is a similar view at right angles to Fig. 1.

I have illustrated the improvement applied to a forging press, but it is equally 40 adapted for flanging, bending and other presses, hence the improvement is not confined in its application to any particular kind of press, but is applicable to all apparatus of the several types above referred to.

The base or lower fixed platen 5 of the press rests upon the shoes 6, which are similar to the shoes commonly used in mills for supporting heavy machinery, and carries the 50 die or other tool 7. This base or platen is located over the well 8, and is provided with a series of openings for the sleeves 10, four in the present instance, which are rigid with the movable base member 11, and move with 55 the same. The lower movable base member

carries the four cylindrical columns 12 secured at their upper ends the upper movable platen 13 provided with the die or other suitable tool 14. This upper platen is carried and supported by the columns 12, and the latter pass through the sleeves 10 on the lower movable base member 11 and are screw threaded as at 15, at their lower ends. 60

The lower movable base member 11 is hollow and carries four worm wheels 16, each of 65 which has an integral nut 17, meshing with the threads 15 on the columns 12, the worm wheels being seated on the lower member 18 of the movable base member, and the nuts mounted in the sleeves 19 depending from 70 said lower member. The four worm wheels 16 mesh with the worm shaft 20 mounted in the movable base member, and the said shaft is preferably driven by an electric motor connected thereto by a universal coupling. 75

Mounted in bearings 21 in the base or fixed platen 5 is the shaft 22, carrying gear wheel 23 which is geared up to any suitable motor. Shaft 22 is provided with two 80 cranks or eccentrics 24 (eccentrics being shown) upon which the movable base member 11 and all the parts carried thereby, are supported by the yokes 25, which are integral with or rigidly secured to the said 85 movable base member and embrace the eccentrics 24 as shown. Bearings or bushings 26 are interposed between the yokes 25 and the eccentrics 24 at the top, and pitmen 27 are interposed between the eccentrics and the 90 bearings 28 carried by the lower movable base member immediately below the eccentrics. Bearings or bushing 26 have a sliding contact with the underside of the yokes 25, and the pitmen 27 have rocking contact 95 on the bearings 28, so that as the eccentrics revolve, the bushings 26 and pitmen 27 rock laterally and impart an upward or downward movement to the movable base member 11 and parts carried thereby, the direction 100 of such movement being dependent of course on the direction of movement of the eccentrics. The pitmen 27 and bushings 26 are cut away at the side as shown in Fig. 2, to permit of the necessary rocking movement 105 of these parts without contacting with the columns 12 between which they are located.

The bearings 28 which carry the pitmen 27 are supported on the wedge blocks 29, which are held in position and adjusted by 110

the screw rods 30 and nuts 31, the rods 30 being anchored to the cross member 32 which is a part of the movable base member and is located between the lower ends of the pitmen 27 and operates to hold the latter against inward displacement.

The yokes 25 above referred to are integral or rigid with the sleeves 10, and support the movable base member 11 and the parts carried thereby directly on the eccentrics of the shaft 22, and the sleeves 10 are mounted in the base of fixed platen 5, and are adjusted and held in proper relative position by the wedges 33 which are secured in place by the screw bolts 34, the said wedges being located at the upper and lower margins of the base so as to afford extended bearings for the sleeves.

With the construction as above described, by rotating worm shaft 20 in one direction, the four worm wheels 16 and their nuts 17, will be rotated in a direction to elevate the four columns 12, the upper platen 13 and the die or other tool 14, and by reversing the direction of rotation of the said shaft 20, the columns and upper platen and its die will descend, the movable base member 11 being suspended from the crank shaft 22. In the operation of the device, the upper die or tool 14, will be lowered onto the work, and apply the initial forging or bending pressure to the work on the die or other tool 7, by rotating the worm wheels through shaft 20, and after the upper die has applied this initial pressure to the work, the power or working stroke of the upper die 14 is accomplished by rotating the shaft 22, which acting through the pitmen 27, forces the movable base member 11 and all the parts carried thereby downwardly a distance equal to the throw of the eccentrics, or as much of said distance as the character of the work will permit. If for instance in bending plates, the eccentrics make a complete revolution, the upper platen can be again lowered onto the work by the worm, and a second power or working stroke applied through the eccentrics, and this operation can be repeated as many times as may be necessary to complete the work. After the work has been forged, bent or otherwise acted upon, the upper platen is elevated by rotating the worm shaft 20 in a direction to elevate the columns 12.

In making the power stroke, all parts of the press except the base or fixed platen 5, move downwardly, whereas in the initial stroke, the columns 12 move down through the base 5 and movable base member 11, which latter is then suspended from the shaft 22.

While I have shown and referred to the shaft 22 as provided with eccentrics, it is evident that it may have cranks hence I would have it understood that the term ec-

centric is intended to include cranks or their equivalent. It is also evident that other changes might be resorted to without departing from my invention, hence I would have it understood that I do not confine myself to the construction or details shown but consider myself at liberty to make such changes as may come within the spirit of the invention and scope of the claims.

Having fully described my invention, what I claim as new and desire to secure by Letters-Patent, is:—

1. In a press for flanging, forging, etc., the combination of a fixed base, a movable base member, a movable upper platen, gearing carried by the movable base member for imparting the first or initial movement to the upper platen, and means within the fixed base for imparting the working stroke to the upper platen through the movable base member.

2. In a press for flanging, forging, etc., the combination of a fixed base having a die or other tool, a movable base member, means for raising and lowering the latter, an upper platen carried by said movable member and movable therewith and means for moving the upper platen independently of the movements of the movable base member.

3. In a press for flanging, forging, etc., the combination of a base having a die or other tool, a movable base member, means carried by said base for suspending and for raising and lowering said movable base member, an upper platen carried by the said movable member, and means carried by the latter for imparting independent vertical movement to the upper platen.

4. In a press for flanging, forging, etc., the combination of a fixed base having a die or other tool, a vertically movable base member below said fixed base, means for moving said movable member, a platen above the fixed base and carried by said movable member and means on latter for moving the upper platen vertically independently of the movements of the movable base member.

5. In a press for flanging, forging, etc., the combination of a fixed base, a movable base member, threaded columns carried by the said base member and carrying the upper platen and its tool, nuts mounted in the movable base member and engaging the threads on the columns, gearing for rotating said nuts, and means within the fixed base for imparting the working stroke to the upper platen through the lower movable base member.

6. In a press for flanging, etc., the combination of a fixed base, a shaft journaled therein and provided with eccentrics, a movable base member suspended from the eccentrics of said shaft, an upper platen carried by the movable base member, means

on the latter for imparting the initial stroke to the upper platen, and means for rotating the shaft.

7. In a press for flanging, forging, etc.,
5 the combination of a fixed base, a shaft journaled therein and provided with eccentrics, a movable base member suspended from the eccentrics of said shaft, a series of vertical columns carried by said movable
10 base member, an upper platen carried by said columns, means on the said movable base member for moving the columns vertically and means for rotating the shaft for imparting the working stroke to the upper
15 platen.

8. In a press for flanging, forging, etc., the combination of a fixed base, a shaft journaled therein and provided with eccentrics, a movable base member having
20 sleeves guided in openings through said fixed base, means suspending said movable base member from the eccentrics of said shaft, nuts mounted in the movable base member under and in line with the said
25 sleeves, means for rotating the nuts in unison, threaded columns engaging said nuts and passing upwardly through the sleeves, an upper platen carried by the columns at their upper ends and means for rotating the
30 shaft.

9. In a press for forging, flanging, etc., the combination of a fixed base, a shaft journaled therein and provided with eccentrics, a movable base member suspended
35 from the eccentrics of said shaft and provided with sleeves which project upwardly through the fixed base, columns passing through the sleeves, a platen secured to the upper ends of said columns, means on the
40 movable base member for moving the columns vertically, and means for rotating the shaft.

10. In a press for flanging, forging, etc., the combination of a fixed base, a shaft
45 journaled therein and provided with eccentrics, a movable base member having yokes embracing the eccentrics on the shaft, columns passing through the fixed base and

supported by the movable base member, means carried by the latter for imparting 50 vertical movement to said columns, a platen secured to the upper ends of the columns, and means for rotating the shaft, whereby the working stroke will be imparted to the upper platen through the movable base 55 member and columns.

11. In a press for flanging, forging, etc., the combination of a base, a shaft journaled therein and provided with eccentrics, a movable base member having yokes straddling 60 the eccentrics, pitmen between the eccentrics and movable base member, columns carried by said movable base member and passing upwardly through the base, an upper platen carried by said columns, and 65 means for actuating the shaft.

12. In a press for flanging, forging, etc., the combination of a base, a shaft journaled therein and provided with eccentrics, a movable base member having yokes straddling 70 the eccentrics, pitmen between the eccentrics and movable base member, devices for adjusting said pitmen, columns carried by the movable base member and passing upwardly through the base, an upper platen 75 carried by said columns, and means for rotating the shaft.

13. In a press for flanging, forging, etc., the combination of a base carrying a die or other tool, a shaft journaled in the base and 80 provided with eccentrics, a movable base member having yokes straddling the eccentrics, pitmen between the eccentrics and movable base member, columns carried by said movable base member and passing up- 85 wardly through the base, an upper platen carried by said columns and means carried by the movable base member for moving the columns vertically.

In testimony whereof I have signed this 90 specification in the presence of two subscribing witnesses.

WILLIAM HENRY MORGAN.
